US00D953140S

(12) **United States Design Patent** (10) **Patent No.:** **US D953,140 S**
(45) **Date of Patent:** **** May 31, 2022**

(54) **HANDLE**

(71) Applicant: **WHIRLPOOL CORPORATION**,
Benton Harbor, MI (US)

(72) Inventors: **Daniel Chow**, St. Joseph, MI (US);
Daniel V. Clements, St. Joseph, MI (US);
Christopher A. Gregory, St. Joseph, MI (US); **Patrick J. Schiavone**, Benton Harbor, MI (US); **Rex Wilson**, St. Joseph, MI (US)

(73) Assignee: **Whirlpool Corporation**, Benton Harbor, MI (US)

(**) Term: **15 Years**

(21) Appl. No.: **29/589,132**

(22) Filed: **Dec. 28, 2016**

(51) LOC (13) Cl. **08-06**

(52) U.S. Cl.

USPC **D8/316**

(57) **CLAIM**

We claim the ornamental design for a handle, as shown and described.

DESCRIPTION

FIG. 1 is a front perspective view of a handle of the present disclosure;

FIG. 2 is a front elevational view of the handle of FIG. 1; FIG. 3 is a rear elevational view of the handle of FIG. 1; FIG. 4 is a first side elevational view of the handle of FIG. 1;

FIG. 5 is a second side elevational view of the handle of FIG. 1;

FIG. 6 is a top plan view of the handle of FIG. 1; and, FIG. 7 is a bottom plan view of the handle of FIG. 1.

The broken lines depict portions of the article that form no part of the claimed design.

1 Claim, 3 Drawing Sheets
